UNITED STATES PATENT OFFICE.

STEPHEN B. GRAY, OF JACKSONVILLE, ILLINOIS.

BUSTLE.

SPECIFICATION forming part of Letters Patent No. 359,860, dated March 22, 1887.

Application filed May 12, 1885. Serial No. 165,265. (No model.)

To all whom it may concern:

Be it known that I, STEPHEN B. GRAY, of the city of Jacksonville, in the county of Morgan and State of Illinois, have invented a new and useful Skirt-Supporter and Bustle, of which the following is a specification, reference being had to the annexed drawings, in which—

Figure 1 is a perspective view of my improved skirt-supporter and bustle. Fig. 2 is a vertical central section of the same applied to the body. Fig. 3 is a detail view showing the waistband and sacks broken away. Fig. 4 is an interior view of the bags and covering, showing one of the springs in side elevation.

This invention relates to improvements in skirt-supporters and bustles, which improvements will be fully understood from the following description, when taken in connection with the annexed drawings.

Referring to the drawings by letters, A designates the improved bustle; and B, the waistband, having shoulder-straps f f, which are crossed behind and attached to this band, as shown in Fig. 1.

The improved bustle A is composed of coiled springs a a c, arranged vertically and incased in an inner fabric forming vertical pockets or bags d, preferably three in number, and each pocket having a coiled spring in it. The upper end of the wire forming each spring is suitably attached to the waistband B, and the lower end of this wire is loosely looped around the last coil at e, so that it is allowed free play. The highest coil of each spring is attached by a fastening, h, to the waistband B, so that the position of each spring can be varied as desired by tightening or loosening their fastening.

In the drawings, Fig. 1, I have represented three springs arranged in separate bags or pockets having closed bottoms; but I may increase

the number of springs and pockets according to the width of bustle required. The inner fabric forming the said pockets is inclosed in an outer fabric covering, j, which serves as a shield to prevent the clothing of the wearer from taking the form of the springs in the pocketed fabric. The larger or outer fabric covering, j, should be applied loose enough to allow the springs to act freely, but not to bag or furrow between the pockets inclosing the springs, and the closed bottoms of the pockets are fastened in a suitable manner to the bottom of the outer fabric covering.

Having described my invention, I claim—

1. In a bustle, the combination, with the inner fabric having vertical pockets therein, and coil-springs arranged in said pockets, of the outer fabric covering, the latter serving as a shield to prevent the clothing of the wearer from taking the form of said springs in said pocketed fabric, substantially as specified.

2. In a bustle having coil-springs inclosed in closed bottom pockets, the outer fabric covering having its bottom attached to the bottoms of said pockets, substantially as described.

3. As a new and improved article of manufacture, a bustle and skirt supporter consisting of pockets inclosing coil-springs attached to the waistband, the outer inclosing fabric attached by its bottom to the bottoms of the said pockets, the adjustable attachments h, connecting the coil-springs to the waistband, and the slipping connections e of the said springs, all constructed and adapted to operate substantially in the manner and for the purposes described.

STEPHEN B. GRAY.
